CLAIM

U.S. PATENT DOCUMENTS

The ornamental design for an accessory for an electronic device, as shown and described.

DESCRIPTION

D249,326 S * 9/1978 Johanson D8/367
D269,410 S * 6/1983 Johansson D8/367
D269,411 S * 6/1983 Johansson D8/367
D431,341 S * 9/2000 DiPaolo D3/208
D513,419 S * 1/2006 Morrison D20/28
D575,816 S * 8/2008 Law D19/10
D632,949 S * 2/2011 Rowley D8/356
D691,438 S * 10/2013 Appleby D8/40
D713,240 S * 9/2014 Chance D8/356
D764,461 S * 8/2016 Romanoff D14/453
D818,802 S * 5/2018 Iwahara D8/356
D820,584 S * 6/2018 Axelrod D3/203.1
D823,710 S * 7/2018 Schone D11/86

FIG. 1 is a front perspective view of an accessory for an electronic device, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof; and,

FIG. 9 is a front perspective view thereof in an environment of use.

The broken lines of even length depict portions of the accessory for an electronic device that form no part of the claimed design.
